UNITED STATES PATENT OFFICE.

GEORGE LOWRY, OF ROSEVILLE, OHIO.

FLOWERPOT DIE.

Application filed October 26, 1926. Serial No. 144,376.

The object of the invention is to provide means for use in connection with the die employed by potters in the formation of vessels and pots, such as flower pots, so that the upper edge of the product may be readily cleaned by the rotation of the spinner head prior to removing the molded piece from the mold; and to provide a construction of this character wherein the cleaning element may be rendered inactive during the molding operation and yet automatically brought into operative position upon the completion of the molding operation.

With this object in view, the invention consists in a construction and combination of parts of which a preferred embodiment is illustrated in the accompanying drawings, wherein:

Figure 1 is a view, partly in section and partly in elevation, showing a flower pot molding machine having a die equipped with the improvement constituting the invention.

Figure 2 is a horizontal sectional view on the plane indicated by the line 2—2 of Figure 1.

Figure 3 is a transverse vertical sectional view on the plane indicated by the line 3—3 of Figure 2.

The die employed in the present invention is of the usual form consisting of the head ring 10 and the plunger 11, being mounted for rotary movement in the spinner head 12 and axially aligned with the mold 14 which is movable in the usual manner toward and away from the die by any conventional means, such as a foot pedal 15.

After the pot 16 has been formed by the rotation of the die through the medium of the spinner head, accompanied with the elevation of the mold, there is left at the outer edge of the pot adjacent the mold wall a thin film of clay which, in the ordinary procedure, must be disposed of by hand prior to the removal of the pot from the mold. The present invention comprises means for mechanically removing this film and such means comprises scraper pins 17 extending slidably through the head ring 10 in the direction of the axis of the die, these pins protruding beyond the lower face of the head ring to engage the top edge of the pot adjacent the peripheral wall of the mold.

The pins 17 are slidably mounted in the

head ring but are carried by radial bars 18 disposed on top of the head ring and projecting peripherally beyond the latter for connection with the posts 19 which at their lower ends are formed with cups 20 receiving the balls 21. The posts are slidably mounted in bearings 22 secured on the peripheral surface of the head ring and rigid connections are effected between the posts and the bars 18.

The posts are yieldingly impelled downwardly to bring the outer ends of the bars into engagement with the upper ends of the bearings 22, flat springs 23 secured on the upper face of the head ring and bearing upon the upper ends of the posts serving this purpose. The inner ends of the bars 18 are mounted between spaced guide pins 24 secured in the upper face of the head ring and the pins 17 are adjustable in the bars by means of set-screws 25 threaded through the bars and bearing upon the pins.

In the operation of a die equipped with the invention, the mold is raised as the die is rotated until finally the balls 21 bear upon the peripheral flange 26 of the mold. As the product contained in the mold assumes shape and the elevation of the mold continues, the posts 19 are raised in the bearings until the mold approaches the under face of the head ring, at which time the molding operation is complete. The mold is then dropped with the result that the springs 23 depress the posts and in so doing move the bars 18 down toward the head ring, the scraper pins at this time being extended from the bottom face of the head ring. Then the rotation of the spinner head effects the cleaning operation at the upper edge of the pot where it adjoins the mold, the pins scraping the corner clean of the film of clay contained therein. By means of the set-screws 25, the extent of projection of the cleaning or scraping pins 17 may be determined.

The invention having been described, what is claimed as new and useful is:

1. A pot die for use with a spinner head and a cooperating mold, the same being provided with scraper elements disposed adjacent the periphery of the mold at the upper edge in one position of the die with relation thereto, the scraper elements being movably mounted in the die and automatically re-

tracted into inoperative position on the full depth of penetration of the die into the mold.

2. In combination with a pot mold and a cooperating die, a scraper element carried by the die and engageable in the upper corner formed by the molded product with the mold, the scraper element being mold-actuated for moving into inoperative position upon the full depth of penetration of the die into the mold.

3. In combination with a pot die and a cooperating mold, the latter having a peripheral flange and the former comprising a head ring and a plunger, a scraper element slidably mounted in the head ring for protrusion beyond the lower face thereof and engageable in the corner formed by the molded product with the mold, a post slidably mounted on the head ring and having a foot bearing upon the mold flange in one position of the latter, and operative connections between the post and the scraper element for retraction of the latter beyond the lower face of the head ring upon certain relative positions of the mold and die.

4. In combination with a pot die and a cooperating mold, the latter having a peripheral flange and the former comprising a head ring and a plunger, a scraper element slidably mounted in the head ring for protrusion beyond the lower face thereof and engageable in the corner formed by the molded product with the mold, a post slidably mounted on the head ring and having a foot bearing upon the mold flange in one po-

sition of the latter, and a bar secured to the post and overlying the head ring, the scraper element being carried by said bar.

5. In combination with a pot die and a cooperating mold, the latter having a peripheral flange and the former comprising a head ring and a plunger, a scraper element slidably mounted in the head ring for protrusion beyond the lower face thereof and engageable in the corner formed by the molded product with the mold, a post slidably mounted on the head ring and having a foot bearing upon the mold flange in one position of the latter, and a bar secured to the post and overlying the head ring, the scraper element having an adjustable mounting in said bar.

6. In combination with a pot die and a cooperating mold, the latter having a peripheral flange and the former comprising a head ring and a plunger, a scraper element slidably mounted in the head ring for protrusion beyond the lower face thereof and engageable in the corner formed by the molded product with the mold, a post slidably mounted on the head ring and having a foot bearing upon the mold flange in one position of the latter, a bar secured to the post and overlying the head ring, the scraper element having an adjustable mounting in said bar, and a spring mounted upon the head ring and bearing upon the upper edge of the post.

In testimony whereof he affixes his signature.

GEORGE LOWRY.
